UNITED STATES PATENT OFFICE

151,065

DESIGN FOR A FRUIT JAR AND BOTTLE OPENER

Henry L. Nichols, Los Angeles, Calif.

Application May 3, 1946, Serial No. 129,283

Term of patent 14 years

(Cl. D44—29)

To all whom it may concern:

Be it known that I, Henry L. Nichols, a citizen of the United States, residing in the city of Los Angeles, county of Los Angeles, State of California, have invented a new, original, and ornamental Design for a Fruit Jar and Bottle Opener, of which the following is a specification, reference being had to the accompanying drawing, forming a part thereof.

Fig. 1 is a plan view of the fruit jar and bottle opener, showing my new design.

Fig. 2 is an edge view of the fruit jar and bottle opener illustrated in Fig. 1.

I claim:

The ornamental design for a fruit jar and bottle opener, as shown.

HENRY L. NICHOLS.
